(57) **CLAIM**

The ornamental design for a fill valve, as shown.

DESCRIPTION

FIG. 1 is a bottom perspective view of the valve;
FIG. 2 is a top perspective view of the valve;
FIG. 3 is a side elevation view of the valve. A view of the
opposite side would be a mirror image of FIG. 3;
FIG. 4 is a front side elevation view of the valve;
FIG. 5 is a top plan view of the valve; and,
FIG. 6 is a bottom plan view of the valve.
